[57] **CLAIM**

The ornamental design for a thigh support pad for a continuous passive motion carriage, substantially as shown and described.

DESCRIPTION

FIG. 1 is a perspective view of a thigh support pad for a continuous passive motion carriage, showing our new design, the continuous passive motion carriage being shown in broken lines for illustrative purposes only and forming no part of the claimed design;

FIG. 2 is a top plan view of the thigh support pad;

FIG. 3 is a side elevational view of the thigh support pad, with the side opposite that shown being a mirror image;

FIG. 4 is a bottom plan view thereof, the broken lines representing conventional stitching, and

FIG. 5 is an end elevational view thereof, with the end opposite of that shown being a mirror image.
